UNITED STATES PATENT OFFICE

DANIEL S. BEATTIE, OF ATLANTA, GEORGIA, ASSIGNOR TO NATHAN MANUFACTURING COMPANY, OF NEW YORK, N. Y., A CORPORATION OF NEW YORK

OPERATING MECHANISM FOR INJECTORS

Application filed June 18, 1929. Serial No. 371,950.

This invention relates to mechanism for operating injectors, that is apparatus for feeding water into boilers under pressure, and is particularly adapted for use with injectors of the non-lifting type as applied to locomotives. Injectors of this type are usually operated in the following manner well-known in the art.

Water is allowed to run into the injector 10 body by opening a valve attached to the injector until it issues at the overflow. Steam is then admitted through an independent valve to the nozzles within the body of the injector where the velocity of the steam is imparted to the mass of the water so that the momentum of the two which is greater than the pressure within the boiler, permits the water to be forced into it. It is thus apparent that to operate the injector two distinct 20 motions are necessary. First, that of opening the water valve; second, that of opening the steam valve.

It is the principal object of this invention to combine the two aforesaid operations into 25 one by the employment of suitable devices which use a fluid medium, such as steam, to start and stop the operation of the injector.

Another object is to eliminate entirely the opening and closing of the water valve but to 30 adjust it to the required degree and keep it in that position, and prevent spilling of water at the overflow when the injector is inoperative by shutting off the overflow simultaneously with the steam valve. Other objects 35 will become apparent as the nature of the invention is better understood after a perusal of the following specification and an inspection of the accompanying drawings in which

Fig. 1 shows a diagrammatic, fragmentary, 40 elevational view of a locomotive to which is attached an injector of the non-lifting type in connection with a standard three-way operating valve especially adapted to be used with these improvements;

Fig. 2 is an enlarged elevational view, partly in section, of an injector in an open or feeding position embodying a preferred form of my improvements;

Fig. 3 is a similar view showing the injector 50 in a closed position or at rest;

Fig. 4 is a plan view of the injector turned at an angle of 90 degrees; and

Fig. 5 is a fragmentary sectional view of the steam valve operating mechanism in a modified form.

Like numbers of reference denote similar parts throughout the several views and the following specification.

10 is a fragmentary part of a locomotive to one side of which is attached an injector 11 of the non-lifting type, having a steam connection 12, a water connection 13, a delivery connection 14, and an overflow connection 15. The steam connection 12 is attached to an elbow 16 at the top of the injector 11 forming, 60 preferably, an integral part therewith. A steam pipe 17 leads from the steam connection 12 to a main shut-off valve 18 at a turret 19 on top of the boiler within the cab.

20 is a steam nozzle screwed into a wall 21 separating a steam chamber 22, in communication with steam pipe 17 by connection 12, and a water chamber 23 which communicates with a water pipe 24 from the tender (not shown) coupled to the injector by means of connection 13. 25 is a water valve controlling 70 a port 26 through which water is admitted into the chamber 23. Water valve 25 is operated by means of a valve handle 27 located in a convenient position within the cab and fastened to a rod 28 which is connected to the valve by means of a universal joint 29 as clearly shown in Fig. 1.

Screwed into the top of injector 11, adjacent to elbow 16 and in alignment with steam nozzle 20 is a housing 30, closed at its outside by a cap 31. This housing is bored out interiorly at 32 and concentrically therewith to a somewhat smaller diameter at 33 to receive a differential piston head 34 composed of a large piston 35 and a small piston 36, slidably engaging, respectively, inner bores 32 and 33 of the housing. The lower end of the piston head 34 is reduced to a spindle 37 to which is suitably fastened a valve disc 38 90 adapted to seat on the inlet end of the steam nozzle 20. The top of the piston head 34 is provided with small lugs 39 adapted to contact with the bottom of cap 31 for the purpose of keeping the main portion of the top 95 100

of the piston head in spaced relation with the cap. The head 34 is hollowed out at its top forming with the bottom of cap 31 a pressure chamber 40. 41 is a vent through the side of the housing 30.

42 is an overflow casing at the side of the injector 11 having within it an opening 43 communicating with the water and mixing chambers around the nozzles of the injector so that through this opening water or a mixture of water and steam may freely pass into passages 44 and thence by way of an overflow pipe 45, coupled on to the injector by connection 15, into the atmosphere or ash-pit or other desirable point of discharge. Opening 43 is controlled by a vertically operating check 46 which has a substantially flat disc 46^a closing the opening, and a fluted guide 47 above it. 48 is a housing screwed into the top of the overflow casing 42 and bored out interiorly for a piston 49 adapted to reciprocate within it. The lower end of piston 49 is tubularly shaped at 50 and telescopes over the fluted guide 47 of check 46. The top of piston 49 is slightly cupped to form with the upper inner part of housing 48 a pressure chamber 51. 52 is a spring coiled around the tubular extension 50 below piston 49, resting against a collar 53 screwed into the open bottom of the housing 48 to act as a stop for the spring which tends to force the piston upwardly against the top of the housing.

54 is a pipe fitting screwed into the top of housing 48 having suitably connected to it a small pipe 55. 56 is a cross fitting screwed into cap 31 of housing 30 interiorly bored out and provided with a relatively small bore 57 on that branch which screws into the cap. One side branch of the cross 56 has connected to it the aforesaid small pipe 58 extending upwardly into the cab of the locomotive. The other side branch of the cross has screwed onto it a heater valve 68 preferably of standard angle valve, needle type, construction. This heater valve has a pipe 69 connecting it to a coupling stud 70 screwed into the injector body below its valve controlled water port 26, thus establishing communication between the steam pipe 58 and the water end of the injector.

Mounted in the cab, convenient to the engine driver, is a three-way cock 59, of the usual construction well-known in the art, having an inlet 60 connected to a dry steam supply by means of a pipe 61, one of its outlets 62 to pipe 58 and its other outlet 63 to a pipe 64 open to the atmosphere. A lever 65 is used to operate the cock as will be explained more fully hereinafter.

60 The operation of the device is as follows:

The injector is shown at rest in Fig. 3. In this position the water valve 25 is open and the injector body filled with water. The three-way cock 59, in the position illustrated in Fig. 1, admits steam from pipe 61 to pipe

58 by way of cross fitting 56 and forces the piston head 34 downwardly until the valve disc 38 seats upon the steam nozzle 20, thus cutting off the steam supply to the nozzles.

The area of the piston 35 of the head 34 being larger than the area of the smaller or lower piston 36, keeps the valve disc 38 closed against the pressure below it. Simultaneously steam passes through small pipe 55 and fitting 54 into pressure chamber 51 and forces the piston 49 downwardly, compressing spring 52 until the lower end of extension 50 of the piston seats on check 46 and thus closes the overflow opening 43. It is obvious that in this position by virtue of the closing of opening 43 no water can be spilled at the overflow.

In order to place the injector in a feeding position, the handle 65 is turned about 90 degrees, when the steam supply from pipe 61 is cut off by the cock 59 and when simultaneously steam from the pipe 58 is exhausted through the cock to the atmosphere. The steam pressure within pipe 17 and steam chamber 22 then forces the disc 38 from its seat and acting against the under side of piston 36 raises the piston, the pressure chamber 40 being open to the atmosphere. The small bore 57 in the cross fitting retards the motion of the piston head 54 so that steam is admitted into the nozzles gradually in accordance with best engineering practice. At the same time steam is exhausted from pressure chamber 51 through pipe 55 which communicates with pipe 58 permitting spring 52 to force the piston 49 upwardly, so that check 46 is free to open. While starting the injector and until the jet is established which forces the water into the boiler against the full boiler pressure, it is necessary to provide an outlet for the water at the overflow; after the jet is established, check 46 closes automatically and prevents the drawing in of air through opening 43. In Fig. 2 is clearly shown the position of the operating mechanism of the injector while feeding.

In connection with the modified form of steam valve operating mechanism shown in Fig. 5, a four-way cock is employed instead of the three-way cock above described. This four-way cock is also of a construction well-known in the art. With this modification, in order to start the injector, steam is admitted from the operating cock by way of a pipe 66 below the piston 36^a which reciprocates within a pressure chamber 40^a, a stem 37^a being fluid-tightly and slidably mounted within a collar 67 at the bottom of the pressure chamber. Simultaneously, as explained before in connection with the three-way cock, pipes 58 and 55 exhaust to the atmosphere through the operating cock. In order to stop the injector, steam is admitted to pipe 58 and thence to pipe 55 and simultaneously pipe 66 is exhausted to the atmosphere by way of the oper-

ating cock. This closes the steam valve 38 and simultaneously the overflow check 46.

The water valve 25 is open at all times as stated before. Spilling of the water at the overflow when not feeding is prevented by the closing of the check 46. It is obvious therefore, that where the engine driver formerly had to operate two valves, viz, a valve admitting steam to the nozzles and the water valve from closed to open positions, it is with these improvements only necessary to operate one valve, namely the three-way cock 59 which controls the steam supply to the nozzles and simultaneously opens or closes the overflow. The water valve 25, while shown with an operating handle extended into the cab, can be left in a position adjusted to suit requirements and need not be disturbed thereafter, except should it be desired to examine or repair the overflow piston mechanism in which case it should be closed to stop the waste of water at the overflow. For all practical purposes, therefore, if so desired, the operating handle and rod for the water valve 25 may be entirely omitted and the valve set by other suitable means right at the injector body, thus relieving congestion in the cab.

A valve 18 is applied in the steam line to the injector only to act as a main shut-off in case of repairs. No operating valve intermediate the main valve and the injector is needed, the operating cock 59 being used instead.

In order to heat the water in the tender of the locomotive, heater valve 68 is opened and steam admitted through pipe 58 and by way of the water connection of the injector to the tender. With the arrangement shown in Fig. 2 as well as the modification illustrated in Fig. 5, the steam supply to the heater valve 68 is automatically cut off as soon as pipe 58 in both figures is exhausted to the atmosphere through the operating cock. In this manner manual opening or closing of the heater valve when starting the injector is entirely eliminated and in cold weather, due to the needle type construction of this valve, a small amount of steam will always be admitted into the tender while the injector is inoperative.

One of the principal advantages of the invention resides in the fact that because the steam pipe right up to the injector steam nozzle is filled with steam or water of condensation under pressure, water hammer due to the sudden admission of steam from the steam inlet valve heretofore in use is entirely eliminated. With these improvements steam is gradually admitted directly into the nozzles and does not strike an inert body of water with full force.

Because the opening of the steam and overflow valves by means of the arrangement described herein is practically simultaneous the

usual waste of water at the overflow which occurs when two independent valves are operated is cut down to the lowest possible minimum.

It is understood that various other changes of form, proportions and minor details of construction may be resorted to without departing from the principles or sacrificing any of the advantages of the invention as defined in the appended claims.

What I claim as new, is:

1. Means to operate a non-lifting injector, comprising an independent valve adapted to control the admission of steam to the injector nozzles by fluid pressure, a water valve in fixed adjustment, and an overflow check, the said independent valve having means to hold the said check in closed position when no steam is admitted to the injector nozzles, and means to relieve the fluid pressure from above the said check to permit the check to open simultaneously with admission of steam to the said nozzles.

2. In a non-lifting injector, an overflow check, a piston adapted to close the said check, an independent operating valve having means controlling the admission of steam to the injector nozzles, means to close by fluid pressure the said check, and means to force the said piston from closing contact with the said check as soon as the fluid pressure is removed therefrom simultaneously with the admission of steam to the nozzles.

3. In a non-lifting injector having a steam valve controlling the admission of main steam to the injector nozzles, a water valve, an overflow check adapted to be opened to permit the overflow of water from the injector when starting, a piston connected to the said steam valve, and a piston operably connected to the said overflow check, an operating valve adapted to admit steam simultaneously to one side of each of the said pistons for the purpose of, respectively, closing the said steam valve and holding the said overflow check in a closed position.

4. In a non-lifting injector, a steam valve, an overflow check adapted to reciprocate freely when the injector is in operation, and common means adapted to close the said steam valve and simultaneously the said overflow check by fluid pressure.

5. In a non-lifting injector, a pressure chamber, a piston adapted to be reciprocated within the chamber, a steam valve connected to the said piston, another pressure chamber, a piston adapted to be reciprocated within the said other chamber, an overflow check adapted to contact with the piston in the said other chamber, and common means to admit fluid pressure to both said pressure chambers for the purpose of closing the said steam valve and the said overflow check.

6. In a non-lifting injector, a pressure chamber, a piston adapted to be reciprocated

within the chamber, a steam valve connected to the said piston, another pressure chamber, a piston adapted to be reciprocated within the said other chamber, an overflow check adapted to contact with the piston in the said other chamber, and common means to admit fluid pressure to both said pressure chambers on top of both the said pistons for the purpose of closing the said steam valve and the said overflow check, the said steam valve being opened by the fluid pressure below the piston connected to it automatically and the said overflow check being free to reciprocate as soon as the fluid pressure is removed from their respective pressure chambers.

7. In a non-lifting injector, a pressure chamber, a piston adapted to be reciprocated within the chamber, a steam valve connected to the said piston, another pressure chamber, a piston adapted to be reciprocated within the said other chamber, an overflow check adapted to contact with the piston in the said other chamber, and common means to admit fluid pressure to both said pressure chambers for the purpose of closing the said steam valve and the said overflow check, the said steam valve opening automatically and the said overflow check being free to reciprocate as soon as the fluid pressure is removed from their respective pressure chambers, and a spring adapted to force the said other piston away from the said check when the fluid pressure is removed from the said other chamber, to permit the check to be opened freely.

8. In a non-lifting injector, a steam valve, an overflow check adapted to reciprocate freely when the injector is in operation, a heater valve controlling the supply of steam to the water connection of the injector to heat the water in the tender, normally open when the injector is inoperative, and common means adapted to close the said steam valve and simultaneously the said overflow check by fluid pressure and simultaneously admit steam to the said heater valve.

9. In a non-lifting injector, a pressure chamber, a piston, means to admit fluid pressure to the chamber at one side of the piston and means to exhaust the chamber at the other side of the said piston for the purpose of reciprocating the piston, a steam valve adapted to be closed by the said piston, another pressure chamber, a piston within the said other chamber, an overflow check, means to admit fluid pressure to one side of the piston in the said other chamber to force the piston to keep the said overflow check closed while the said steam valve is closed, and means to open the said overflow check automatically as soon as the said steam valve is opened.

In testimony whereof I have hereunto set my hand.

DANIEL S. BEATTIE.
